UNITED STATES PATENT OFFICE.

EMIL STEINHORST AND WILLIAM C. STEINHORST, OF UTICA, NEW YORK, ASSIGNEES
TO EMIL STEINHORST & SONS, INC., OF UTICA, NEW YORK.

FURNACE.

Application filed February 27, 1926. Serial No. 91,143.

Our present invention relates to furnaces for warming air and designed particularly to use gas or liquid fuels.

The purpose of our invention is to provide 5 a warm air furnace especially adapted to use fluid fuels, that is either gas or liquid fuel with convenience, safety and efficiency.

A further purpose is to provide a furnace 10 of the type mentioned of such construction, arrangement and combination of its parts that the furnace will be adapted to utilize the heat from the fuel consumed to the greatest possible advantage; adapted to resist the rusting or corrosive action which 15 tends to take place due to the presence of moisture and particularly sulphurous acid within the heater upon condensation of the gases and especially to provide for such condensation to take place where it will do no 20 harm to the heater and where the condensation can be removed from the gases before they pass into the chimney.

Another object of our invention is to provide 25 a heater of the type indicated where the parts with which the gases of combustion come into contact are made of relatively thin light-weight moisture-resisting and acid-resisting material and with said material preferably sheet metal or tubing, said 30 sheet metal and tubing further preferably being of copper. This lightness of structure enables the whole furnace and in many cases even the outer casing thereof to be completely assembled in the factory or shop and 35 transported bodily to the basement where it is available for immediate operation upon making the connections for the fluid fuel, incoming cold air, outgoing warm air and smoke pipe and condensation drain.

40 Another advantage of the light weight of our heater is that it begins to give an appreciable supply of warm air practically at the instant of going into operation for the reason that the furnace does not have the 45 usual mass or thickness of metal to be heated before the air passing therethrough is heated. This substantially instantaneous heating operates not only when the furnace is first put into operation but at each time 50 when the thermostatic automatic control turns on the fuel. The fact that the combustion chamber, flues and gathering or condensation chamber of the furnace are of sheet metal or tubing and preferably sheet 55 copper or copper tubing results in the device

getting a very large percentage of the heat from the products of combustion into the air being warmed on the other side of this thin metal and where copper is used any especially highly heated part of the metal will 60 transfer its heat rapidly and to a great distance through the copper so that said heat may be absorbed by the air at other points. The possibility of making a warm air heater of this light weight construction and getting 65 the great advantages thereof results from appreciating that a furnace designed exclusively to use fluid fuel does not have to follow the excessively heavy construction that has always been used with solid fuel 70 and used heretofore, as far as we are aware, even with fluid fuel.

Still further purposes of our invention are to provide a furnace of the class described where many flues or pipes are used 75 to pass the gases through and these flues are arranged so that there is a very ready and extensive circulation of air past said flues; and further preferably to have said flue pipes of a special type of construction in 80 order to radiate the heat from said flues into the surrounding part by means of fins or flanges projecting from said pipes at closely spaced intervals.

Fig. 1 is a view looking at the front of a 85 furnace embodying our invention, said view being partly a front elevation, partly a vertical sectional view just within the front of the casing and partly a vertical sectional view through the upper right hand portion 90 of the combustion chamber.

Fig. 2 is a view mostly in longitudinal central section through the furnace with the rear portion of the combustion chamber and that part of the flues and all of the gathering 95 chamber shown in side elevation.

Fig. 3 is a detailed sectional view on an enlarged scale illustrating the form of the flues and their connection to the chambers

Referring to the drawings in a more particular description it will be seen that our furnace comprises a combustion chamber 10, burners 11 therein, a large number of flues 12 leading from the upper part of said combustion chamber downwardly preferably on 100 both sides thereof to the gathering and condensation chamber 13 spaced below the combustion chamber.

From the base 14 there extend upwardly four uprights 15 conveniently formed of 110

angle iron and located at the four corners of the combustion chamber 10. Between the forward pair of these uprights and rigidly secured thereto is an inverted V-shaped stirrup or bracket 16 and a similar bracket is located between the two rear uprights 15. Upon these two brackets rests the combustion chamber 10 with the angles of the uprights 15 enclosing the four corners of the greater part of said combustion chamber. Near their upper ends the front pair of uprights and the rear pair of uprights are connected by transversely extending cross bars 17 which cross bars extend beyond the combustion chamber and beyond the flues 12 to the casing 18. The opposite ends of each cross bar are turned at a right angle to the length of the cross bar forming convenient means to locate and brace the casing at the two sides thereof near the front and rear ends of the furnace. Just outside the combustion chamber the front and rear cross bars 17 are tied together by longitudinal strips 19. The combustion chamber 10 is somewhat irregular in shape but preferably is so formed as to be rectangular in cross section at any plane. The main portion of the combustion chamber it will be seen is a plain rectangular box but its bottom is V-shaped with the bottom walls 20 sloping downwardly to each other as appears in Fig. 1 with the front edges of these walls resting upon the V-shaped brackets 16. The upper part of the combustion chamber as seen in transverse section is roughly shaped like an hour-glass in that the side walls of said combustion chamber first slope towards each other as at 21 as they extend upwardly and then extend directly upwardly as at 22 forming a neck portion of reduced size and then the side walls again flare outwardly as they continue upwardly as at the surfaces 23. Above the slanting portions 23 the side walls extend directly upward for a very short distance to meet the flat top 24.

In the front end of the combustion chamber there is provided a door aperture 25 through which are placed into the combustion chamber the burners 11 and through which also is admitted the air to support combustion when the furnace is in operation. As shown in the drawings this aperture is provided with a forwardly extending flange 27 extending to or just through the casing at the front of the furnace to form a passage-way leading from without the furnace to the inside of the combustion chamber. To the outer end of this flange 27 is secured the correspondingly five-sided door frame 28 upon which is hinged the door 31.

About midway the height of this door frame the door 31 ceases but has hinged thereto the air door 62. The door 31 is provided with a panel 30 of transparent ma-

terial as mica or the like so that the operator may see the condition of the flame at the burners. The door 62 has an outwardly extending ear 32 to which may be attached the chain 33 to control as hereinafter mentioned the extent to which the door is opened. The particular type of the fluid fuel burner is no part of our invention. We have illustrated our furnace as using an approved form of gas burner 11. As indicated in the drawings eight such burners are usually arranged in two rows of four burners each extending longitudinally, that is from front to rear of the combustion chamber. The different burners in each row are connected by short lengths of pipe 34 which provide passage ways for the fuel between adjacent burners. In the system of burners illustrated in the drawings gas is separately supplied to each row of burners through pipe 35 connected to the front end of the front burner. This pipe 35 extends forwardly part way through the passage formed by the flange 27 and then turns laterally through the side portions of the said flange to the horizontal runs of pipe 36. The pipes 36 from the opposite rows of burners extend laterally from the opposite side portions of the flange 27 just within the front of the casing 13 and then extend through the sides of said casing. From this point pipes 37 extend forwardly and upwardly to a line outside of the front casing and at a level above the door frame and then horizontal runs of pipe 38 bring the supply lines to a common inverted T 39. To the third or larger end of this T is connected the main single supply pipe 40. In this supply pipe 40 preferably at a point just above the front door of the furnace is provided a quick-acting valve 41 with a forwardly extending lever 42. To this valve lever 42 is connected the chain 33 coming up from the air supply door 31 with said chain operated as required by a motor (not shown) which motor is thermostatically controlled. It will be obvious of course that our furnace could be used without thermostatic control, that is the supply of gas and air could be manually regulated as needed but for ordinary purposes the thermostatic control is advantageous in order to get the proper even temperature desired with as small a consumption of fuel as possible.

The burners 11 are supported at the proper elevation within the combustion chamber by two or more of the burners in each row being rested upon the top cross bar 43 of a triangular support formed from said cross bar 43 and converging side pieces 44 which side pieces 44 rest against the converging bottom portions 20 of the combustion chamber. The two or more of these triangular supports that are used are permanently connected and held upright by

connecting strips 45. A horizontal plate 46 extends from the cross piece on the door frame inwardly to the front burners so as to carry the incoming air to the bottom of the burners and prevent it from being drawn up in front of the first pair of burners. Beyond this plate 46 it will be understood that the burners are arranged closely enough in the rows and that the rows are arranged 10 closely enough to each other and to the adjacent walls of the combustion chamber to allow only the proper amount of air to go up past the burners as distinct from the air that is drawn up into the burners.

15 The gathering or condensation chamber 13 already mentioned as being spaced below the combustion chamber is generally of the shape of a long square box arranged at an angle so that it has two upper sides 48 and 49 meeting at an angle of ninety degrees and two lower sides 50 and 51. The lower angle of this long box, however, is cut off by a flat bottom 47 which slopes downwardly as it extends from the front of the condensation chamber to the rear thereof in order to provide for a positive flow of the moisture of condensation within this chamber to the drain pipe 52. It will be understood that the front of this condensation chamber is 30 closed as by front end 53 but that the rear end of this chamber projects outwardly through the outer casing 18 and thereafter is shaped into circular form to connect with the large pipe 54 which extends upwardly to 35 the chimney. The drain pipe 52 is connected to the lowest point of the condensation chamber just outside the casing 18.

Preferably as already suggested the combustion chamber 10 and the condensation chamber 13 will be constructed of sheet metal and preferably this sheet metal will be of such material as to withstand the moisture and the sulphurous acid present in said moisture when condensation takes place as 45 the gases of combustion are cooled to a relatively low temperature. Preferably as such moisture and acid-resisting material we use copper as said material has the added advantage of being a good conductor of heat.

50 From the upper part of the combustion chamber, that is from the sloping sides 23 thereof to the upper and sloping sides 48 and 49 of the combustion chamber 13 there extend the flues 12. As will be seen from 55 the drawings there are a great number of these flues arranged on both sides of the combustion chamber and preferably arranged in more than one row or series of flues on each side of the combustion chamber. In practice we use as shown in Fig. 1 two rows of 60 such flues on each side of the combustion chamber as this combines the necessary number of flues and convenience of manufacture and assembling thereof with a very general 65 or extensive circulation of the air between

the flues on each side of the combustion chamber. The flues of both the inner and outer rows extend downwardly and outwardly as at 12^b from the sloping portion 23 of the side wall of the combustion chamber to a point about on a level with the cross bars 17. From here the flues extend downwardly to about the level of the burners and preferably in this central portion 12^a the flues slant slightly inward. The lower portion 12^c of each flue then slants sharply inward to its upper side 48 or 49 of the condensation chamber 13.

These flues 12 are preferably formed of copper pipe and with the pipe of relatively small diameter, for example about three-quarters of an inch in diameter so that all parts of the current of gases of combustion may be close enough to a radiating surface to give up its heat. To further increase the radiation from these flues 12 they are preferably formed with fins or a continuous spiral fin 55 projecting outward radially from the pipe.

As indicated in the drawing this fin 55 on each flue 12 begins as close to the ends of the flue as is practicable for assembling purposes and extends the whole length of the flue. The ends of the flues may be attached in any convenient way to the sheet metal of the gathering chamber and to the sheet metal of the combustion chamber. Preferably such fastening will be effected by forming upon the flue a short distance from its end an encircling outwardly-projecting rib 56 which will bear against the outer surface of said sheet metal with the end of the pipe extended through a suitable sized aperture in the said sheet metal and then turned back from the hole on the inside of the sheet metal as flange 57 which construction forms a joint which is strong mechanically and gas-tight.

Near the bottom of the casing 18 are provided apertures for the connection to the furnace of the usual incoming cold air conduits 58. In the top of the casing are provided the necessary number of openings to which are attached the usual conduits 59 to conduct the warm air from the top of the furnace.

On top of the combustion chamber there is preferably placed a long evaporating tray or pan 60 to which the water is supplied by a small supply pipe 61 extending through the upper portion of the casing. This arrangement provides a supply of water for evaporation where it is most readily absorbed by the heated air.

In our furnace as shown in Fig. 2 it will be noticed that the rear end of the furnace is also provided with a flanged doorway extending from the combustion chamber through the outer casing with a door frame and air supply door 62 on the main door 31

the same as at the front of the furnace. This air supply door 62 is also connected by chain 63 to the same motor or other raising means as is the chain 33 for the front door. 5 In this way the air supply for the burners is introduced at both ends of the furnace tending to equalize the combustion at the burners. It will be understood that this additional air supply at the rear end of the 10 furnace is not an absolute essential to the furnace, but is we believe the preferred modification to further aid in procuring most efficient combustion of the fuel.

Our construction of furnace is peculiarly 15 adapted to be enlarged to produce larger sizes of furnaces as may be required for larger houses or buildings. Such enlargement is obtained by lengthening the combustion chamber, gathering chamber and of course the casing and adding proportionately 20 more flues and by inserting in the enlarged combustion chamber one or more additional fluid-fuel burners. It will be noticed that this enlargement of the furnace is entirely 25 in adding to its length and to the parts in the length of the furnace, but that the transverse construction of the furnace is not changed. This is an advantage from the manufacturing standpoint as the same sizes 30 of parts can be used for the front and rear casings, the front and rear of the combustion chamber and the front and rear doors and also especially the two sizes and lengths of flue can be used for any such length of 35 furnace. Of course for much larger sizes of furnaces the whole dimensions both transversely and in height may be increased but this is not necessary for the ordinary range of sizes required for the usual houses and 40 other buildings.

As already suggested, the flow of the gases resulting from combustion at the burners will be from the burners up through the combustion chamber to the enlarged upper 45 portion thereof; then laterally to its opposite sides and to and through the great number of flues 12. Through these flues the travel of these hot gases will be downwardly for a relatively long distance in proportion 50 to the size of the furnace, that is to the common gathering or condensation chamber 13 located below the combustion chamber. The direction of travel of the air being warmed is directly contrary or reverse to the travel 55 of the gases in the flues 12. In other words, the air coming back from the house to be warmed through the cold air inlets 58 is at once diverted upwardly by the condensation chamber 13 and then travels upwardly 60 surrounding the flues 12. In this upward travel of the air it passes between the closely spaced flues and is especially effective in absorbing the heat from the flues because the air not only passes upwardly along the 65 flues but most of the air has to pass from

outside the flues to the inside of the flues to the space 65 about two-thirds of the way up upon the combustion chamber due to the said flues even in their middle portion slanting outwardly to a point very close to 70 the casing 18. The movement of the air into this portion is also accelerated by reason of this portion of the combustion chamber being very hot and so very rapidly heating the air in contact therewith. From the 75 space 65 the air again travels upwardly and then outwardly through the upper sloping portions 12^b of the flues. In all of this travel of the air past the flues the fins on said flues help to break up and thoroughly 80 distribute the traveling air and at the same time impart the heat from the flues to the air. It will be seen, therefore, that in the upward travel of the air past the combustion chamber most of the air will have been 85 twice passed through the spaces between both rows of flues on either side of the furnace. This additional contact or travel of air is very helpful in getting a complete and rapid heating of the air. It will be noticed 90 also that the incoming cold air from the air inlets 58 is first brought into contact with the lower end of the flues where the gases of combustion have been most condensed and cooled off and that as the air ascends it 95 will be successively brought into contact with warmer portions of the flues until as the air gets to the top of the flues and to the top of the combustion chamber the air is in contact with the hottest portion of the furnace. The cooling of the gases of combustion by the heat being abstracted therefrom by the air is so marked in our furnace that when the gases of combustion leave the condensation chamber 13 they are at a temperature 100 of about 110° Fahr.

With the gases of combustion condensed to this low temperature it will be obvious that a great deal of moisture will be present in the lower portion of the flues and particularly in the condensation chamber 13. This sharp condensation of the gases of combustion helps greatly toward inducing the downward travel of the gases through the flues 12 in that the gases are being cooled 115 as they travel down through said flues. This moisture gathering in the lower portion of the flues runs down the flues into the condensation chamber and this moisture and further moisture condensing in the condensation chamber 13 runs down the slanting bottom of the condensation chamber to the drain pipe 52 as also does some condensation occurring in pipe 54. In this way substantially all moisture is removed from the 120 gases of combustion before they are conducted into the chimney, and what little moisture remains in the gases is absorbed by the very considerable quantity of air mixed with the gases at this last stage either 125 130

through the usual check draft in the so-called smoke pipe or through an additional opening provided in the chimney which opening is left open at all times.

5 The extremely low temperature of the gases of combustion at the end of the travel of the gases through the flues or at what is commonly called stack temperature, which temperature as mentioned tests as low as 10 110° Fahr., indicates of course that the heat has been taken from the gases to the air being warmed to a much greater extent than heretofore. In many furnaces burning solid and in most furnaces burning fluid-fuel this 15 temperature of the gases at the vent outlet is from 300 to 500 degrees Fahr. or even several hundred degrees higher. This escape of the gases at such a high temperature is wasteful of fuel and more so when 20 the higher priced fuels as oil and especially gas are being used. Such high temperature at the vent to the stack has heretofore been thought necessary and in fact was necessary where iron or steel parts were used for the 25 furnace. This high vent or stack temperature took away the gases before any considerable condensation thereof into moisture took place. An appreciable condensation into water with sulphurous acid present 30 would soon rust or eat away the iron or steel of the furnace and so was to be avoided even though involving what was thought to be merely a theoretical or at least an unavoidable waste of fuel. By making our 35 combustion chamber, flue pipes and gathering chamber of copper or other acid-resisting and rust-resisting material, we have produced a furnace where such condensation is not harmful and therefore a furnace 40 where condensation can be carried as far as possible and so fuel saved that has heretofore been wasted.

The use of copper or other acid-resisting material and the especially efficient construction of our furnace in other respects has enabled us to produce a furnace that uses either oil or gas fuels efficiently enough to be active competitors with solid fuel furnaces notwithstanding the greater relative cost of the oil and especially the manufactured gases.

50 It will be understood of course that exact parity of cost of fuel is not necessary to allow oil and especially gas burning furnaces to compete with furnaces using solid fuels. The gas burning furnaces entirely eliminate the trouble, dirt and expense of getting the fuel into the cellar, and putting it into the furnace, then removing the 55 ashes daily from the furnace and periodically from the cellar.

Our gas burning furnace with thermostatic-control is especially convenient and efficient in fuel consumption because of its 60 being able to be started instantaneously

and being thrown back to use only the minimum flame at the burners when more heat has become unnecessary.

The arrangement of our furnace is such that after the furnace has been once lit or put 70 into operation the burners will continue to burn with a minimum flame even though the thermostatic control has moved the lever of the gas valve 41 to closed position. Preferably this is accomplished by providing a 75 hole 64 in the disk 65 of the said valve. It will thus be seen that even though the disk of the valve has been closed a small amount of gas will pass through the valve. This hole is purposely made of such size that 80 enough gas will be admitted to keep all of the burners lighted with about as small a flame as can be safely used. This provides a small amount of heat and enables all of the burners to light at once to full 85 capacity when the valve 41 is again turned on. With this arrangement the furnace may be lit in the fall and can remain in operation until it is turned off the next spring.

What we claim as new and desire to secure by Letters Patent is:

1. In a warm-air furnace, the combination of a sheet copper combustion chamber, fluid-fuel burners in the lower part of the combustion chamber, a plurality of flues leading from the upper part of the combustion chamber, a gathering chamber to which the flues are connected, a vent pipe leading from the gathering chamber to the chimney, a drain pipe leading from the lower part of the gathering chamber, a casing surrounding said combustion chamber, gathering chamber and flues, an inlet for cold air near the base of the casing and means connected to the upper part of the casing for conducting the warm air from the furnace. 100

2. In a warm-air furnace, the combination of a sheet copper combustion chamber, fluid-fuel burners in the lower part of the combustion chamber, a plurality of copper flues leading from the upper part of the combustion chamber, a gathering chamber to which the flues are connected, a vent pipe leading from the gathering chamber to the chimney, a drain pipe leading from the lower part of the gathering chamber, a casing surrounding said combustion chamber, gathering chamber and flues, an inlet for cold air near the base of the casing and means connected to the upper part of the casing for conducting the warm air from the furnace. 110

3. In a warm-air furnace, the combination of a copper combustion chamber, fluid-fuel burners in the lower part of the combustion chamber, a plurality of flues leading from the upper part of the combustion chamber, a gathering chamber having sheet copper walls to which the flues are connected, a vent pipe leading from the gathering chamber 115 120 125

to the chimney, a drain pipe leading from the lower part of the gathering chamber, a casing surrounding said combustion chamber, gathering chamber and flues, an inlet 5 for cold air near the base of the casing and means connected to the upper part of the casing for conducting the warm air from the furnace.

4. In a warm-air furnace, the combination 10 of a combustion chamber, fluid-fuel burners in the lower part of the combustion chamber, a plurality of copper flues leading from the upper part of the combustion chamber, a gathering chamber to which the flues are 15 connected, a vent pipe leading from the gathering chamber to the chimney, a drain pipe leading from the lower part of the gathering chamber, a casing surrounding said combustion chamber, gathering chamber and flues, an inlet for cold air 20 near the base of the casing and means connected to the upper part of the casing for conducting the warm air from the furnace.

5. In a warm-air furnace, the combination 25 of a combustion chamber, fluid-fuel burners in the lower part of the combustion chamber, a plurality of copper flues leading from the upper part of the combustion chamber, a copper gathering chamber to which the 30 flues are connected, a vent pipe leading from the gathering chamber to the chimney, a drain pipe leading from the lower part of the gathering chamber, a casing surrounding said combustion chamber, gathering 35 chamber and flues, an inlet for cold air near the base of the casing and means connected to the upper part of the casing for conducting the warm air from the furnace.

6. In a warm-air furnace the combination 40 of a copper combustion chamber, fluid-fuel burners in the lower part of the combustion chamber, a plurality of copper flues leading from the upper part of the combustion chamber, a copper gathering chamber to 45 which the flues are connected, a vent pipe leading from the gathering chamber to the chimney, a drain pipe leading from the lower part of the gathering chamber, a casing surrounding said combustion chamber, gathering 50 chamber and flues, an inlet for cold air near the base of the casing and means connected to the upper part of the casing for conducting the warm air from the furnace.

55 7. In a warm-air furnace the combination of a combustion chamber, fluid-fuel burners in the lower part of the combustion chamber, a gathering chamber below the level of the burners, a plurality of flues leading 60 continuously downward from the upper part of the combustion chamber to the upper part of the said gathering chamber, a vent pipe leading from the gathering chamber to the chimney, a drain pipe leading from the 65 lower part of the gathering chamber, a cas-

ing surrounding said combustion chamber, gathering chamber and flues, an inlet for cold air near the base of the casing and means connected to the upper part of the casing for conducting the warm air from 70 the furnace.

8. In a warm-air furnace the combination 75 of a combustion chamber, fluid-fuel burners in the lower part of the combustion chamber, a sheet copper gathering chamber below the level of the burners, a plurality of flues leading continuously downward from the upper part of the combustion chamber to the upper part of said gathering chamber, a vent pipe leading from the gathering chamber to the 80 chimney, a drain pipe leading from the lower part of the gathering chamber, a casing surrounding said combustion chamber, gathering chamber and flues, an inlet for cold air near the base of the casing and means connected to the upper part of the casing for conducting the warm air from the furnace.

9. In a warm-air furnace the combination 85 of a combustion chamber continuous and compact in cross area, fluid-fuel burners in 90 the lower part of the combustion chamber, a gathering chamber below the level of the burners, a plurality of flues leading continuously downward from the upper part of the combustion chamber to the upper part of the said gathering chamber, a vent pipe leading from the gathering chamber to the chimney, a drain pipe leading from the lower part of the gathering chamber, a casing surrounding 95 said combustion chamber, gathering chamber and flues, an inlet for cold air near the base of the casing and means connected to the upper part of the casing for conducting the warm air from the furnace.

10. In a warm-air furnace, the combination 100 of a combustion chamber, fluid-fuel burners in the lower part of the combustion chamber, a gathering chamber below the bottom of the combustion chamber, a multitude 105 of small, closely spaced flues located on the opposite sides of the combustion chamber and extending from the upper part of the combustion chamber continuously down to the upper part of said gathering chamber, a vent pipe leading from the gathering chamber to the chimney, a drain pipe leading from the lower part of the gathering chamber, a casing surrounding said combustion chamber, gathering chamber and flues, an inlet for cold air near the base of the casing and means connected to the upper part 110 of the casing for conducting the warm air from the furnace.

11. In a warm-air furnace, the combination 115 of a combustion chamber, fluid-fuel burners in the lower part of the combustion chamber, a gathering chamber below the bottom of the combustion chamber, a multitude of small, closely spaced, circumferentially finned flues located on the opposite sides of the com- 120

125

- bustion chamber and extending from the upper part of the combustion chamber continuously down to the upper part of said gathering chamber, a vent pipe leading from 5 the gathering chamber to the chimney, a drain pipe leading from the lower part of the gathering chamber, a casing surrounding said combustion chamber, gathering chamber and flues, an inlet for cold air near the base 10 of the casing and means connected to the upper part of the casing for conducting the warm air from the furnace.
12. In a warm-air furnace, the combination of a combustion chamber, fluid-fuel 15 burners in the lower part of the combustion chamber, a gathering chamber below the bottom of the combustion chamber, a multitude of small, closely spaced flues located on the opposite sides of the combustion chamber 20 and extending from the upper part of the combustion chamber continuously down to the upper part of said gathering chamber, a vent pipe leading from the gathering chamber to the chimney, a drain pipe leading from 25 the lower part of the gathering chamber, a casing surrounding said combustion chamber, gathering chamber and flues, an inlet for cold air near the base of the casing and means connected to the upper part of the casing for 30 conducting the warm air from the furnace, said flues being arranged in a plurality of rows on each side of the combustion chamber and slanting intermediate their ends nearly to the casing and then back to 35 the gathering chamber whereby air admitted to the casing has to travel inwardly between said flues and then outwardly between said flues.
13. In a warm-air furnace, the combination of a combustion chamber compact in 40 cross area, fluid-fuel burners in the lower part of said combustion chamber, a gathering chamber below the combustion chamber, a multitude of relatively small, closely spaced 45 tubular flues extending in a slanting direction continuously downwards from the upper portion of the combustion chamber to the gathering chamber, a vent pipe leading from the gathering chamber to the chimney, a drain pipe leading from 50 the lower part of the gathering chamber, a casing surrounding said combustion chamber, gathering chamber and flues, an inlet for cold air near the base of the casing and means connected to the upper part of the casing for conducting the warm air from the furnace, 55
14. In a warm-air furnace the combination of a combustion chamber compact in cross area, fluid-fuel burners in the lower part of said combustion chamber, a gathering chamber below the combustion chamber, a multitude of small closely spaced tubular flues provided with circumferentially extending fins, said flues extending continuously from the upper portion of the combustion chamber 60 downwards to the gathering chamber, a vent pipe leading from the gathering chamber to the chimney, a drain pipe leading from the lower part of the gathering chamber, a casing surrounding said combustion chamber, 65 gathering chamber and flues, an inlet for cold air near the base of the casing and means connected to the upper part of the casing for conducting the warm air from the furnace. 70
15. In a warm-air furnace, the combination of a combustion chamber alike transversely throughout its length, fluid-fuel burners in the lower part of said combustion chamber, a gathering chamber alike transversely throughout its length and located 75 below and parallel with the combustion chamber, a multitude of small closely spaced tubular flues extending from the upper portion of two opposite sides of the combustion chamber downwards to the correspondingly arranged opposite sides of the gathering chamber, a vent pipe leading from the gathering chamber to the chimney, a drain pipe leading from the lower part of the gathering chamber, a casing surrounding 80 said combustion chamber, gathering chamber and flues, an inlet for cold air near the base of the casing and means connected to the upper part of the casing for conducting the warm air from the furnace, 85
16. In a warm-air furnace, the combination of a combustion chamber compact in cross area, fluid-fuel burners in the lower part of said combustion chamber, a gathering chamber below the combustion chamber, a multitude of relatively small, closely spaced tubular flues extending in a slanting direction continuously downwards from the upper portion of the combustion chamber to the gathering chamber, a vent pipe leading from the gathering chamber to the chimney, a drain pipe leading from 90 the lower part of the gathering chamber, a casing surrounding said combustion chamber, gathering chamber and flues, an inlet for cold air near the base of the casing and means connected to the upper part of the casing for conducting the warm air from the furnace, different sizes of 95 the furnaces being made by varying the length of the sides of the combustion chamber, of the gathering chamber and of the sides of the casing and the number of flues used and using the same units for flues and for ends of the combustion chamber, gathering chamber and casing. 100

In witness whereof we have affixed our signatures, this 6th day of February 1926.
